DOOR OPERATED SPRAY DEVICE

Paul J. Ash, Reading, Pa.

Application June 20, 1951, Serial No. 232,551

2 Claims. (Cl. 299—82.5)

1

This invention relates to door operated devices of the atomizing or spraying type, and more especially to devices that are adapted for operation by the opening and closing movement of a door so as to periodically introduce a certain atomized liquid into a bathroom, clothes closet, or other room for one purpose or another.

One object of my invention is to provide a novel device of the type indicated.

Another object is to provide such a device which has certain structural and functional features of advantage over the similar devices of the prior art.

A further object is to provide such a device which includes a replaceable container as well as means whereby the container can be quickly and easily exchanged.

It is also an object to provide such a device which can be quickly and easily adjusted for uniform operation.

Another object is to provide such a device which can be quickly and easily installed on any door frame for operation by the swinging movement of the door.

A further object is to provide a novel door operated device of the indicated type which is simple and inexpensive in construction and can be universally applied for various purposes.

With these and other objects in view, which will become more readily apparent from the following detailed description of the practical and illustrative embodiment of my device shown in the accompanying drawing, the invention comprises the novel device, elements, features of construction and arrangement of parts in cooperative relationship, as more particularly defined by the hereto appended claims.

In the accompanying drawings:

Figure 1 is an elevational view of a portion of a door frame and door having my novel device cooperatively applied thereto.

Fig. 2 is a detail front elevational view of the device with the cover removed so as to disclose certain structural details thereof.

Fig. 3 is a vertical sectional view taken substantially as indicated by the arrows 3—3 in Figure 1.

Fig. 4 is a vertical sectional view taken substantially as indicated by the arrows 4—4 in Figure 2.

Fig. 5 is an enlarged longitudinal sectional view taken substantially as indicated by the arrows 5—5 in Fig. 4.

It will be helpful to a clear understanding of my invention to first briefly consider some of the more important aspects and features thereof, so that these may be kept in mind during the subsequent reading of the detailed description of the practical and illustrative embodiment of my novel device disclosed in the accompanying drawing.

2

Accordingly, it is pointed out that the atomizing device may be used for example, to deliver a liquid spray or deodorant, or perfume, to eliminate objectionable odors in rooms, or other enclosures, or it may be used to deliver a liquid spray of disinfectant or insecticide to treat the air in a closet so that moths or other insect life cannot exist therein.

The construction of the device is such that the parts thereof may be inconspicuously mounted on the door and door frame and arranged in such manner that the supply of liquid used in the device can be readily renewed or exchanged.

The liquid to be ejected by the device is preferably stored in a glass container of a certain shape that will fit into a casing designed to also support the spraying mechanism in a predetermined position so that the device can be efficiently door operated in such manner that the spray is accurately directed through an opening in the casing and effectively directed into the room.

Referring now more particularly to the figures of the drawings in which like reference characters indicate like parts, the device comprises a rectangularly shaped casing 1 which is adapted to be fastened to a door frame 2 located above a door 3. Screws 4, which pass through the back of the casing, are used to firmly support and permanently hold the casing in its proper position on the door frame 2 relative to the operating member 5 carried by the door 3.

The casing 1 has a removable cover 6 at the front and in this cover is provided an opening 7 through which the spray is directed by the spraying or atomizing device, as will presently appear. The cover 6 is also provided with an opening 6a which allows the operating member 5 to move into and out of the casing in its movement by the door 3 for the operation of the spraying or atomizing unit of the device hereinafter more particularly described. The cover 6 is adapted to slide in suitable vertical channels 8 formed in each side of the casing and rest in a cross channel 9 at the bottom thereof. In this manner the cover may be raised and entirely removed from the casing by means of a handle opening 10, so as to permit access to the inside of the casing for the insertion of the spray unit or the replenishing of the spray supply.

The spray unit comprises a spray head 11, a liquid tube 12 which leads into the side of the head, a fixed coupling 13 which leads into the bottom of the head and carries at its lower end a compressible bulb 14. Surrounding the liquid tube 12, at its entrance into the head, is a rotatable coupling 15 which is adapted to be threaded to a neck 17 formed on the container 16, a packing flange 18 being interposed between the head and the outer end of the neck so as to tightly seal the head to the container.

The container 16 is preferably made of glass and is positioned as illustrated in Fig. 2 so that its outlet is located in the neck 17 at the right hand and near the top thereof. The container 16 is preferably, but not necessarily, rectangular in shape and has beveled edges at the bottom and rounded edges at the top. Its dimensions are such that it readily fits into the casing 1 behind the cover 6 and holds the spray device suspended in the position illustrated in Fig. 2. A lug 19 in the right hand end of the casing 1 extends substantially to the head 11 of the spray device so as to properly and uniformly locate the spray device and its container in the same position in the casing 1 at all times.

The head 11 of the spray device has an air inlet aperture 20 and a spray outlet or nozzle 21. The inlet aperture 20 is located so as to admit air into the container 16 through the neck 17 thereof so as to keep the contents of the container under constant atmospheric pressure. The spray outlet or nozzle 21 is located in the head substantially at the junction of the extensions of the liquid tube 12 and the air duct in the coupling 13, while the nozzle 21 is so arranged that air forced into the head 11, on the compression of the bulb 14, will be forced through the outlet or nozzle 21, to create a partial vacuum in the head that will cause the atmospheric pressure to force some of the liquid from the container through the tube 12 into the head so as to mix with the air from the bulb and be forced from the nozzle in the form of a spray. In this manner each time the bulb 14 is compressed a quantity of the liquid is drawn from the container and sprayed from the nozzle 21.

As illustrated in Figure 1, the head 11 of the spray unit is located in the casing 1 so that its nozzle 21 is in line with the opening 7 in the cover 6. Any spray developed by the unit will thus immediately be forced out of the casing into the surrounding atmosphere.

The operating member 5 of the device comprises a bracket which, as illustrated in Fig. 3, has an offset upper end that is adapted to move into and out of the opening 6a in the cover 6 and an opening 22 in the bottom of the casing 1 to compress or release the bulb 14 of the spray device. With the door 3 in its closed position, as illustrated in Fig. 3, the bulb 14 is compressed, as illustrated in section in this figure. However, as soon as the door is opened, the operating member 5 is withdrawn from in front of the bulb 14 and moves out of the openings 22 and 6a, so that the bulb can expand to completely fill itself with air.

The bulb 14 is braced at the rear by the lug 23 so that compression of the bulb takes place between this lug and the operating member 5 as soon as the latter moves against the front of the bulb. When the bulb is compressed on the closing of the door, air is expelled from the bulb and forced out of the nozzle 21. As above pointed out, this creates a partial vacuum in the head 11 which causes liquid to be drawn from the container through the tube 12 into the head so as to mix with part of the air that is forced from the bulb and the mixture issues from the nozzle 21 in the form of a spray.

While I have shown and described the spray head 11 as being of a particular construction, it is pointed out that this construction is standard and may be purchased on the open market except for the rotating coupling 15 associated therewith which provides for the adjustable fastening of

the head to the container with a tight seal formed between the head and the end of the neck of the container in any position.

Replacement of the head on the container can thus be readily made and the head adjusted so that its nozzle 21 will be in line with the discharge opening 7 in the cover of the casing.

As illustrated in Fig. 1, the spray device is preferably installed a suitable distance from the hinged side of the door in order to provide the proper movement for the operating member 5 in its compression of the bulb 14 on the closing of the door. The openings 6a and 22 are enlarged to permit an unobstructed arcuate movement of the operating member as it moves in and out of the casing 1 by the swinging movement of the door. Suitable bolts 23-23 are used to fasten the operating member 5 to the door.

Of course, the device herein specifically shown and described may be changed and modified in various ways without departing from the scope of the invention, which is more particularly indicated by the appended claims.

I claim:

25 1. A door operated device of the character described comprising a substantially rectangularly shaped casing, a removable cover at the front of said casing having two predeterminately located openings therethrough, an interchangeable container correspondingly rectangularly shaped to said casing so as to be predeterminately held nested at one end of said casing, a neck projecting from one end substantially at the top of said container, a spray head including a nozzle suspended from said neck and rotatably adjustable thereon to bring said nozzle in alignment with one of the openings in said cover, a compressible bulb suspended from said spray head for operation thereof, and an operating member carried by the door for movement through the other of said openings in said cover into said casing for engagement and compression of said bulb during closing movement of said door.

45 2. A door operated device of the character described comprising, a substantially rectangularly shaped casing having a discharge opening, a substantially correspondingly rectangularly shaped interchangeable container held nested in said casing so as to be predeterminately held in place in one end thereof, a neck projecting from one end near the top of said container into the other end of said casing, an atomizer unit suspended and rotatably adjustable on said neck, a compressible bulb carried by said atomizer unit, an operating member carried by the door for movement into said casing and engagement of one side of said bulb, fixed bracing and locating means provided in said casing for engagement of the opposite side of said bulb to provide predeterminied compression of said bulb between said bracing means and said operating member during movement of said operating member by the door against said bulb.
